UNITED STATES PATENT OFFICE.

PETER M. LARSEN, OF SOUTH BEND, INDIANA.

REFLECTOR.

Application filed July 12, 1924. Serial No. 725,638.

To all whom it may concern:

Be it known that I, PETER M. LARSEN, a citizen of the United States, residing at South Bend, in the county of St. Joseph 5 and State of Indiana, have invented new and useful Improvements in Reflectors, of which the following is a specification.

This invention relates to a reflector and has for its primary object the construction 10 of a reflector by means of which the direction of travel of the light rays from the head light of an automobile may be changed at will by the driver of the automobile.

An object of the invention is to provide 15 adjustable reflector elements which may be thrown at various angles and held in this position.

Besides the above my invention is distinguished in the novel support and arrangement 20 of the reflector elements so that light rays will be prevented from striking the eyes of an approaching driver but will be reflected in a direction to properly illuminate the side of the road.

25 With these and other objects in view the invention will be better understood from the following detailed description taken in connection with the accompanying drawings wherein:

20 Fig. 1 is a side elevation of my improved reflector in applied position.

Fig. 2 is a detailed view of the control mechanism.

Fig. 3 is a sectional view on the line 3—3 35 of Fig. 2.

Fig. 4 is a sectional view on the line 4—4 of Fig. 1.

Fig. 5 is a front elevation of the reflector.

Fig. 6 is a side elevation.

40 Fig. 7 is a top plan view.

Fig. 8 is a sectional view on the line 8—8 of Fig. 7.

Fig. 9 is a sectional view on the line 9—9 of Fig. 2.

45 Again referring to the drawings illustrating one of the many constructions of my invention the numeral 1 designates a clamp for binding engagement around the casing 2 of the headlight. This clamp includes a lower support 3 and upper support 4. Any number of reflecting elements 6 may be used having attached to their lower ends the pintles 7 rotatably mounted in the lower support 3. The upper ends of the reflectors 50 are connected to crank arms 8 passing through the upper support 4 and connected

to the shifter 9. By referring to Figures 7 and 8 it will be seen that the shifter consists of metallic strips 10 and 11 between which is arranged a rubber insert 12. It 60 will be noted that the holes in the strips are larger than the hole 14 in the rubber insert so that the crank arms 8 may have certain limited movement while at the same time be held against vibration or rattling. 65

A bell crank 15 is pivoted to the clamp as indicated at 16 and the lever 17 has a pin and slot connection 18 with the shifter while the other arm 19 is pivotally connected to the control rod 20. This control rod 20 extends rearwardly to be connected to a centrally pivoted lever 21 which in turn is connected to the control handle 22 by the link 23.

By referring to Figures 3 and 9 it will be 75 seen that the lever 21 is provided with a rib 24 moving over the corrugated surface 25 of a disc 26, which is clamped to the post 27 by the clamp 28.

From the foregoing description taken in 80 connection with the accompanying drawing it will be seen that I provide a reflector that the driver of an automobile may very readily change the direction of travel of light rays by operating the handle 22 for shifting 85 the inclination of the reflector elements.

It will also be noted that the parts are 90 readily held in their adjusted position by the lock device illustrated as the rib 24 and corrugations 25.

It is of course to be understood that the reflectors may be arranged in other relations and supported in other manners and shifted in other ways than illustrated, therefore, I do not desire to be limited in any 95 manner except as set forth in the claims hereunto appended.

Having thus described my invention what I claim is:

1. A reflector comprising a support, a 100 plurality of reflector elements supported for swinging movement in the support, a shifter connected to all of the elements to simultaneously swing same, a bell crank lever connected to the support and having a pin and slot connection with the shifter, a rod pivoted to and extending from the bell crank, a centrally pivoted lever pivotally connected to the control rod and provided with a rib, a lock disc cooperating with the 105 rib, and an operating handle, and a link between the lever and operating handle, 110

2. A plurality of reflecting elements supported for swinging movement, means for simultaneously swinging said elements, a control rod connected to said means, a centrally pivoted lever connected to the control rod and provided with a rib, a locking disc cooperating with the rib and means having connection with the centrally pivoted lever for imparting movement to the same.
- 10 3. A plurality of reflecting elements supported for swinging movement, means for

simultaneously swinging said elements, a centrally pivoted lever connected at one end to said means and provided with a rib, a lock disc cooperating with the rib and means having connection with the other end of the pivoted lever for imparting movement to the same and to the reflecting elements. ¹⁵

In testimony whereof I affix my signature.

PETER M. LARSEN.
